(57) CLAIM

The ornamental design for a flashlight, as shown and described.

DESCRIPTION

FIG. 1 is a top plan view of a flashlight showing one embodiment of my new design;

FIG. 2 is a bottom plan view thereof;

FIG. 3 is a left side elevation view thereof;

FIG. 4 is a right side elevation view thereof;

FIG. 5 is a front elevation view thereof; and,

FIG. 6 is a back elevation view thereof.

The broken line showing of the flashlight is for illustrative purposes only and forms no part of the claimed design.
